Primary Examiner — Elizabeth J Oswecki(74) *Attorney, Agent, or Firm* — Amster, Rothstein & Ebenstein, LLP(57) **CLAIM**

The ornamental design for a decorative tree, as shown and described.

DESCRIPTION

FIG. 1 is a front view of a decorative tree showing my new design;

FIG. 2 is a rear view thereof;

FIG. 3 is a left side view thereof, the right side view being a mirror image thereof;

FIG. 4 is a top plan view thereof; and,

FIG. 5 is a bottom plan view thereof.

The broken lines shown in the drawings represent portions of the decorative tree that form no part of the claimed design.
